—fig. 1.

—fig. 2.

fig. 3.

fig. 4.

FIG. 5.

FIG. 6.

FIG. 1 is a side elevation of an infant's training chair showing our new invention and showing in dotted lines a receiving vessel mounted thereon;

FIG. 2 is a front elevation thereof;

FIG. 3 is a plan view thereof;

FIG. 4 is a rear elevation thereof;

FIG. 5 is a plan view thereof, but showing the lid in raised position; and

FIG. 6 is a perspective view of a modified form of the infant's training chair shown in FIGS. 1-5 and differing therefrom in the elimination of the ground-engaging legs.

The dominant features of our invention are shown in full lines.

This application is a continuation of copending application Serial No. D. 84,353, filed March 19, 1965, and now abandoned.

We claim:

The ornamental design for an infant's training chair, as shown and described.
